No. 633,732.

Patented Sept. 26, 1899.

G. W. PRICE.
CENTRIFUGAL PUMP.

(Application filed Mar. 26, 1898.)

(No Model.)

UNITED STATES PATENT OFFICE.

GOMER W. PRICE, OF SAN FRANCISCO, CALIFORNIA.

CENTRIFUGAL PUMP.

SPECIFICATION forming part of Letters Patent No. 633,732, dated September 26, 1899.

Application filed March 26, 1898. Serial No. 675,300. (No model.)

To all whom it may concern:

Be it known that I, GOMER W. PRICE, a citizen of the United States, residing at San Francisco, county of San Francisco, and State of California, have invented certain new and useful Improvements in Centrifugal Pumps; and I hereby declare the following to be a full, clear, and exact description of the same, reference being had to the accompanying drawings, forming a part of this specification.

My invention relates to centrifugal pumps for raising and forcing fluids and to an improved manner of constructing and operating such pumps.

15 My improvement consists in so constructing and arranging the impellers of centrifugal pumps that they are relieved of the resistance caused by the friction of the water on their sides, the water between the impellers and pump-casing being at the sides is discharged therefrom by centrifugal and inductive action, so that the impellers, except on their periphery, revolve in air, or in a partial vacuum.

25 The object of my invention is the avoidance, in part, of resistance to the rotation of the impellers and consequent saving in the amount of power required to raise or impel water by means of these pumps.

30 Referring to the drawings herewith and forming a part of this specification, Figure I is a side view, partially in section, of a centrifugal pump constructed according to my invention. Fig. II is an end view of Fig. I with the suction-pipe and side plate removed. Fig. III is a section through the impeller on the line *x x* in Fig. II, showing the outlets for water from the sides of the impeller. Fig. IV is a section through the impeller on the line *y y* in Fig. III.

35 In centrifugal pumps having incased impellers a principal source of resistance and loss of the driving-power, especially at high speed, arises from the friction of the sides of the impellers on the surrounding water, or in pumps when open or vane impellers are employed by friction of the revolving water against the sides of the pump casing or shell, such friction being the same in either case.

40 To avoid this friction and consequent loss of power, I construct centrifugal pumps as shown in the drawings, 1 being a main frame, 1

on which the various parts are supported, 2 the pump casing or volute for collecting and discharging the water, and 3 the impeller mounted on the spindle 4, driven by the pulleys 5 or in any other suitable manner.

6 is the suction-pipe, and 7 the discharge-pipe.

8 are the main ducts or passages in the impeller, through which the water flows from the inlet at 9, the impeller being of the inclosed or incased type and provided with vanes 10 and 11 on the outside or next to the casing 2. The passages 13 between the vanes 10 and 11 open obliquely inward from the sides of the impeller 3, entering the passage 8 near the point of discharge, as shown in Figs. III and IV. To prevent the entrance of water between the casing and the front or intake side of the impeller 3, I provide a nipple or extension 15 on the end of the suction-pipe 6, that projects a short distance within the impeller 3, the running-joint being parallel to the axis of rotation, as seen in Fig. I, so that the inductive action of the water rushing outward in the passages 8 prevents backflow around the nipple 15. Other features of the pump correspond to common practice and do not require further description.

The operation is as follows: The casing 2 being filled with water, the impeller 3 is set in revolution, and the water in the passages 8 is discharged outward into the volute 12 partly by tangential energy, but mainly by centrifugal force. At the same time the water at the sides of the impeller 3 is driven out by the vanes 10 and 11 and is discharged through the apertures 13, aided, however, by the inductive action of the water in the passages 8, and as there is no supply to these spaces at the sides of the impeller they fill or partially fill with air, so the impeller 3 is subject to air friction only on its sides, thus relieving it of a principal source of resistance. This action of the impeller and of the water at its sides has been ascertained by means of apertures temporarily made through the sides of the casing and is a constant result of the construction shown. The impeller 3 being thus driven without the usual resistance of water friction on its sides, consumes less power for a given work and has otherwise all

the required functions, the same as if immersed in the water all over the exterior surfaces.

Having thus explained and described the nature and objects of my invention and the manner of constructing and applying the same, what I claim as new, and desire to secure by Letters Patent, is—

In a centrifugal pump, a volute casing 2, 10 an inclosed impeller 3 within said casing provided with interior water-passages 8, vanes 10, 11 on the outer sides of said impeller, sweeping the walls of said casing, and passages 13 through the walls of the impeller,

connecting the exterior spaces between the 15 said vanes with the said interior water-passages near the point of discharge, whereby the centrifugal action aided by the inductive action of the outwardly-passing current tends to diminish the contents of the said 20 spaces and reduce the friction between the impeller and the casing, substantially as specified.

GOMER W. PRICE.
